BY
W. H. D. & Co., Attorneys.

UNITED STATES PATENT OFFICE.

PHILIP KURTZ, OF PHILADELPHIA, PENNSYLVANIA.

GOLF-GAME APPARATUS.

Application filed May 12, 1927. Serial No. 190,664.

My invention relates to a new and useful golf game apparatus adapted for use in the practice of golf, and more particularly to the practice of approach shots or putts to develop efficiency and accuracy.

The object of my invention is to provide a portable golf game apparatus which may be readily carried in a golf bag, so that said apparatus may be employed for practice on a golf course, or indoor links or any other suitable place.

Another object of my invention is to provide an adjustable golf game apparatus so that goals of varying diameters may be formed for the reception of golf balls driven or pitched from different angles or distances and by the use of different irons.

A further object of my invention is to provide indicating means for the goal whereby the same is rendered clearly visible at a distance for the guidance of the golfer pitching or driving the ball to said goal, such indicating means being any suitable flag, pennant, shield or wing.

To the above ends, my invention consists of an inner ring or goal comprising an integral ring having an integral diametrical cross bar, an opening or tube in the center of said cross bar and signal supporting means adapted to pass through said opening firmly to secure said ring to the ground or other support.

My invention further consists of an outer ring comprising a plurality of sections detachably secured to each other to form a concentric ring surrounding said inner ring and means for detachably securing the segments of said outer ring in position to ground or other support.

My invention still further consists in providing an adjustable and movable baffle for the inner of said rings to arrest a golf ball after the same has once entered said inner ring.

For the purpose of illustrating my invention, I have shown in the accompanying drawings, forms thereof which are at present preferred by me, since they will give, in practice, satisfactory and reliable results, although it is to be understood that the vari-

ous instrumentalities of which my invention consists can be variously arranged and organized and that my invention is not limited to the precise arrangement and organization of these instrumentalities as herein shown and described.

In the accompanying drawings:

Fig. 1 represents a plan view of a novel golf game apparatus embodying my invention.

Fig. 2 represents a section on line 2—2 of Fig. 1.

Fig. 3 represents a fragmentary view of the underside of the ring segments forming the outer ring shown in Fig. 1.

Fig. 4 represents a fragmentary view of the underside of the ring segments forming the outer ring shown in Fig. 7.

Fig. 5 represents a sectional view showing a modified construction of the ring segments shown in Figs. 3 and 4, in the assembled position.

Fig. 6 represents a section on line 6—6 of Fig. 1.

Fig. 7 represents a view similar to Fig. 1, showing the outer ring enlarged and having a greater number of segments.

Fig. 8 represents a perspective view of a baffle which may be used in conjunction with the inner ring, as shown in Fig. 2.

Referring to the drawings, in which like reference characters indicate like parts, 1 designates an inner integral ring having the integral diametrical cross bar 4 in the center of which is provided the tube or apertured boss 5 having the opening 6 therein, the annular rim 2 of the inner ring 1 being bevelled to facilitate the entry of the ball into the enclosure 3 of said ring. A pin 7 carrying the flag, pennant, or other suitable signal 9 at its upper portion, is adapted to pass through the opening 6 in said boss or tube 5, the lower end of said pin being pointed so as to engage the ground or other suitable support 8, firmly and detachably to secure the inner ring 1 in position, as will be understood from Figs. 1 and 2. 10 designates a baffle having the central recess 11 which engages the pin 7, said baffle being slightly curved (see Fig. 8) and superimposed on the inner ring 1 (see Fig. 2).

95
100

to arrest the golf ball when the same enters the enclosure 3, as will be understood from Figs. 2 and 8. It will be noted that the baffle 10 may be revolved around the pin 7 to face the direction from which the golf ball is being pitched or driven.

Concentric with and surrounding the inner ring or goal 1, is a larger ring composed of a plurality of segments 12, four being shown in Fig. 1 of the drawings, said segments being detachably and adjustably secured to each other so that if desired, a larger ring having a greater number of segments may be assembled, as shown in Fig. 7, where for the purpose of illustration, six segments are employed instead of four, it being understood that the number of segments and therefore the size of said outer ring may be varied without departing from the spirit or scope of my invention. Thus, each segment 12 is provided with an apertured tongue 14 on one end thereof and an apertured recess 15 on the other end thereof, the tongue 14 of each segment 12 being seated in the recess 15 of the adjacent segment. A pin 16 passes through the aligning apertures in said recessed portion 15 and said tongue 14 and extends into and engages the ground or other support 8 as will be understood from Figs. 1 and 6, thus detachably securing the segments 12 to each other and the outer ring as a whole to the support 8.

In Fig. 5 I have shown a modified construction of segments 12 in which I substitute a cut out portion 15* and a lug 14* for the recess 15 and tongue 14 respectively.

By making the recesses or groove 15 in the segments 12 relatively large, and by providing suitably tapered tongues 14 on the other ends of said segments, it is possible to increase the number of segments in the outer ring (see Fig. 7) to provide a larger "goal" when the golfer is practicing shots or putts at relatively longer distances. Thus by tilting the juxtaposed ends of said segments with respect to each other, (see Figs. 4 and 7) I am enabled to employ a greater number of segments 12 and thus produce a larger outer ring, and for this purpose the segments 12 are provided with the elongated apertures or slots 13, through which passes the fastening pin 16, so that the position of the latter may be varied with the expansion or enlargement of said ring and vice versa. The underside or bottom of the segments 12 forming the outer rings, as well as that of the inner ring 1 is flat as will be understood from Figs. 2, 5 and 6, while the upper surface thereof is convexed, bevelled or curved as will be understood from Figs. 1, 2, 5, 6 and 7, to facilitate the entry of the golf ball into the respective enclosures of said rings.

By making the outer ring in a plurality of detachable segments, I render the device of

my invention conveniently portable, since said ring may be taken apart, and the segments thereof, as well as the inner ring 1 and their adjuncts can be easily carried in a golf bag or otherwise.

It will be understood that by novel golf game apparatus may be used without the inner ring 1 if so desired, since when the player desires to practice long approach shots or putts with a midiron, cleek, or driving iron, all that is desired is a relatively large target to aim at, and for that purpose the ring having four segments shown in Fig. 1 or one having a greater number of segments shown in Fig. 7 may be employed, there being no need for the inner relatively small ring 1.

By the use of one or more of these novel devices, I am enabled to create portable golf links, greens and cup for any desired area, on any ground or floor, to be used for practice in lieu of standard golf links, or for use as temporary greens while a regular green is in repair.

The inner ring 1 is provided with the ridges 17 spaced at suitable intervals along the upper bevelled surface of said ring, which serve to deflect the golf ball into the enclosure 3 and to prevent the same from rolling off said bevelled surface. The baffle 10 superimposed on the inner ring 1 is provided with the horizontally disposed forwardly extending flange 16, which also serves to arrest a golf ball and deflect the same into the enclosure 3 of said inner ring 1.

As above stated the cross bar 4 is provided with integral tube or apertured hub 5 by means of which the ring 1 is secured in position to a support, a tube being preferred for use during indoor practice since in that event the pin 7 only serves to support the signal 9 and does not penetrate into the floor. In outdoor practice, either a tube open at both ends or an apertured hub will do as is evident.

It will now be apparent that I have devised a novel and useful construction of golf game apparatus which embodies the features of advantage enumerated as desirable in the statement of the invention and the above description, and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:

1. A portable game apparatus comprising an inner, ring-like receptacle for ball reception, an outer ring arranged concentrically

with respect to the inner ring, and means for securing the outer ring independently of the inner ring.

2. A portable game apparatus comprising an inner, ring-like receptacle for ball reception, an outer ring arranged concentrically with respect to the inner ring, means for extending said outer ring to relatively increase the diameter thereof, and means for securing the outer ring independently of the inner ring.

3. A portable game apparatus comprising an inner, ring-like receptacle for ball reception having ridges spaced along the upper circumference thereof, means including a flag staff and flag for fixing said receptacle to place, an outer ring arranged concentrically with respect to the inner ring, and means for securing the outer ring independently of the inner ring.

4. A portable game apparatus comprising an inner, ring-like receptacle for ball reception, an outer ring arranged concentrically with respect to the inner ring, and means including slotted and co-operative pin parts for securing the outer ring independently of the inner ring.

5. A portable game apparatus comprising an inner, bevelled, ring-like receptacle for ball reception, an outer convexed ring arranged concentrically with respect to the

inner ring, and means for securing the outer ring independently of the inner ring.

6. In a device of the character stated, a sectional ring composed of segments having a convexed top and provided with coacting tongues and grooves having aligning holes therethrough, and pins passing through said holes for securing said segments in assembled position and to the turf during the practicing of approach shots in golf.

7. In a device of the character stated, a sectional ring composed of segments having a convexed top and provided with coacting tongues and grooves having aligning holes therethrough, and pins passing through said holes for securing said segments in assembled position and to the turf during the practicing of approach shots in golf, the grooves in said segments being wider than said tongues so as to permit adjustment of said segments when a varying number of segments are employed.

8. In a device of the character stated, an inner ring like receptacle provided with a transverse bar, a hole therethrough, a pin passing through said hole for securing said ring like member to the turf, and a plurality of wings positioned by said pin and capable of movement thereon.

PHILIP KURTZ.
